UNITED STATES PATENT OFFICE.

MARSHALL LOW, OF WILKINSBURG, PENNSYLVANIA, ASSIGNOR TO WESTINGHOUSE ELECTRIC & MANUFACTURING COMPANY, A CORPORATION OF PENNSYLVANIA.

RADIATOR FOR TRANSFORMER TANKS.

Application filed December 16, 1920. Serial No. 431,102.

To all whom it may concern:

Be it known that I, MARSHALL Low, a citizen of the United States, and a resident of Wilkinsburg, in the county of Allegheny and State of Pennsylvania, have invented a new and useful Improvement in Radiators for Transformer Tanks, of which the following is a specification.

My invention relates to heat-dissipating devices and it has particular relation to apparatus of the above designated character that is adapted for containing electrical or other apparatus normally immersed within a cooling medium.

More specifically, my invention relates to sheet-metal radiators of the type adapted to be mounted upon the outside of a tank or other container and in communication therewith for dissipating heat from the fluid contained therein.

The object of my invention is to provide a radiator of novel construction that shall be relatively light in weight, simple in construction, and inexpensive to manufacture.

Heretofore, it has been customary to construct radiators by connecting together two spaced common header members by means of pipes or tubes. The header members comprise inner walls provided with apertures adapted for the reception of said tubes. An objection to such construction is that it is impossible to vary the amount of radiating area thereof after the installation has been effected.

Another object is that, in carrying repair parts, it is necessary to carry both parts of the header member, as well as a number of the tubes adapted to be disposed therebetween.

By means of my invention, I provide a type of radiator in which the amount of radiating space may be varied at will, either before or after the erection of the apparatus. Another advantage is that each radiator section comprises a plurality of like units and each of the units is constructed of two like parts. Thus, the repair parts to be carried in stock may be of a single standard type only.

Figure 1 of the accompanying drawings is a view, partially in section and partially in side elevation, of a portion of a transformer tank having mounted thereon several units of a radiator constructed in accordance with my invention.

Fig. 2 is a front elevational view of one of two similar segments, which, when united, constitute a unit of the radiator.

Fig. 3 is a side elevational view of the segment illustrated in Fig. 2.

In the drawings, I show a portion of the wall of a tank 4 and a plurality of radiator units 5 mounted thereon. Each of the radiator units consists of two like pressed-metal members 6 which are so bent, that, when fastened together, they constitute a centrally disposed vertically-extending chamber 7 communicating, at its ends, with integral laterally extending passageways 8 and 9, which constitute the top and the bottom, respectively, of each unit.

Each of the segments 6 is provided with a flange 10 extending around the perimeter thereof by means of which the two co-operating segments are welded together to form a unit. Each of the segments is also provided with flanges 11 surrounding the outer ends of the passageways 8 and 9 by means of which each adjacent unit is attached to the next adjacent unit. The entire segment 6 is pressed from a single piece of sheet metal.

Any desired number of the units 5 may be connected to form a radiator, each of the units being supported upon the next adjacent unit. A tubular member 12 having a coupling member 13 mounted thereon is attached to the innermost unit of each radiator, by means of the flange 11. The coupling member 13 is attached to a similar coupling member 14 mounted upon the tank 4, by any suitable means.

The laterally extending chambers 8 and 9 of the outermost units of each radiator may be closed by means of a disk 15 of sheet metal which may be welded to the flange 11 in the usual manner.

From the foregoing description, it will be apparent to those skilled in the art that a radiator constructed in accordance with my invention will be strong and rigid by reason of the fact that the end portions of each unit are integral with the central portions thereof. Also, it is apparent that the amount of radiating surface of the radiator may be varied at will by merely attaching or detaching any desired number of units.

I claim as my invention:

1. A radiator consisting of a plurality

of units each comprising a sheet-metal member pressed to provide a longitudinally-extending passageway merging into a laterally-extending passageway adjacent to each end thereof, said laterally-extending passageways being provided with a flange extending thereabout, said flanges being connected to the flanges of the next adjacent unit.

10 2. A radiator comprising a plurality of units disposed in side-by-side relation, each of said units comprising a plurality of integral complementary portions arranged to form a single longitudinally-extending chamber communicating at each end with a laterally-extending chamber, the walls of the longitudinally-extending chambers of adjacent units being spaced apart and the walls of the laterally-extending chambers being attached to the walls of the next adjacent unit.

20 3. A radiator comprising a plurality of heat-dissipating units, each of said units

comprising a plurality of complementary sections having a central channel portion 25 and end channel portions extending transversely to said central portion, said central and end portions being respectively provided with outwardly extending flanges adapted to be exteriorly welded to similar 30 flanges on the coacting sections to provide a unit having a substantially tubular central portion communicating at each end with transverse tubular header portions, the end portions of said sections being also provided with flanges disposed in planes transverse to the planes of said first mentioned flanges and adapted to co-operate with each other when said sections are secured together to provide continuous flanges adapted 40 to be secured to similar flanges provided on an adjacent unit.

In testimony whereof, I have hereunto subscribed my name this 7th day of December, 1920.

MARSHALL LOW.
